UNITED STATES PATENT OFFICE.

MARY H. BARNES, OF BINGHAMTON, NEW YORK.

SAD-IRON CLEANER.

SPECIFICATION forming part of Letters Patent No. 350,966, dated October 19, 1886.

Application filed August 12, 1885. Serial No. 174,222. (No model.)

To all whom it may concern:

Be it known that I, MARY H. BARNES, of Binghamton, county of Broome, and State of New York, have invented new and useful Improvements in Sad-Iron Cleaners; and I do hereby declare that the following is a full and exact description of the same, reference being had to the accompanying drawings, and to the letters of reference marked thereon.

10 This invention has for its object the cleaning of the face of the iron, and also the application to the same in the act of cleaning of a proper substance for imparting a polish to the article being ironed; and it consists in the combination of a body, A, of wood, of a layer of polishing preparation, and a covering-sheet of perforated sand-paper, substantially as described.

In the drawings, Figure 1 represents a perspective view of my improved sad-iron cleaner; Fig. 2, a transverse sectional view on the line *xx*, Fig. 1; Fig. 3, a partial sectional view, enlarged, on the line *yy*, Fig. 1.

To enable others skilled in the art to make and use my improved sad-iron cleaner, I will proceed to describe fully the construction of the same.

A represents the body portion, of wood, which is covered in any suitable manner, preferably with thick paper *a*, to prevent the wood absorbing the polishing preparation, or from imparting thereto anything injurious. One or more layers of paper may be used, as is desirable. The paper is then covered with one or two thicknesses of cloth, *a'*. The paper and cloth are properly secured to the edges of the block only. The block thus prepared is covered with a suitable preparation, *a''*, Fig. 3, for imparting polish to the article being ironed.

That preferably employed by me consists of the following ingredients: beeswax, white sperm-wax, oil, (best head-light,) and perfumery. This preparation, when it is made liquid by heat, may be readily applied to the fabric on the block by dipping the latter into a receptacle containing it.

B represents a covering-sheet of sand-paper on each side of the block, which is provided with perforations *b*, as shown.

If desired, a band, C, of tin may be employed to inclose the edges of the prepared block.

The operation will be readily understood. When the hot iron is moved over the face of the block to clean it, a sufficient amount of the melted polishing preparation passes through the openings, and is thereby applied to the face of the iron. By means of this special construction the desired results are obtained by a single action. The face of the iron is subjected to the necessary cleaning action, and has applied thereto in the act of cleaning the requisite amount of preparation for imparting a polish to the article being ironed.

It is preferred to prepare both sides of the block for use in the manner described; but, if desired, one side only may be so prepared.

Having thus fully described my invention, what I claim as new, and desire to secure by Letters Patent, is—

In combination with the body A, of wood, the layer of polishing preparation and the covering-sheet of perforated sand-paper.

This specification signed and witnessed this 23d day of June, 1885.

MARY H. BARNES.
